UNITED STATES PATENT OFFICE.

JOSEPH SCHOENFELD, OF ALAMEDA, CALIFORNIA, ASSIGNOR TO THE MAGNAVOX CO.,
OF OAKLAND, CALIFORNIA, A CORPORATION OF ARIZONA.

DESIGN FOR A CASING FOR ELECTRIC HEATERS.

Application filed September 13, 1924. Serial No. 10,770. Term of patent 14 years.

To all whom it may concern:

Be it known that I, JOSEPH SCHOENFELD, a citizen of the United States, residing at Alameda, in the county of Alameda and State of California, have invented a new, original, and ornamental Design for Casing for Electric Heaters, of which the following is a specification, reference being had to the

accompanying drawing, forming part thereof.

The drawing is a perspective view of an electric heater of the wall insert type.

I claim:

The ornamental design for a casing for electric heaters, as shown.

JOSEPH SCHOENFELD.
